SAFETY MILK BOTTLE CONTAINER

William Harold Van Buskirk, Vancouver, British
Columbia, Canada

Application December 2, 1935, Serial No. 52,582

2 Claims. (Cl. 232—41)

My present invention which relates to milk bottle holders generally is more especially designed for apartment house use.

In its generic nature it comprises a wall cabinet or box built into the partition wall between the hall and a room of the apartment, the cabinet having a door at either end; namely, a door at the hall or outer end or side of the cabinet, and a door at the apartment room or inner side of the cabinet. In the cabinet is located a bottle holding slide or suspending member which is secured rigidly to the top of the cabinet and has its ends located adjacent the doors thereof respectively, the end which is adjacent the outer door (the door at the hall side of the cabinet) being provided with a locking device to prevent the unauthorized removal of the bottles, etc.

The invention also resides in the provision of a ticket or money drawer held in the slide against unauthorized removal.

Other objects will in part be obvious and in part be pointed out hereinafter.

To the attainment of the aforesaid objects and ends, the invention still further resides in the novel details of construction, combination and arrangement of parts, all of which will be first fully described in the following detailed description and then be particularly pointed out in the appended claims, reference being had to the accompanying drawings, in which:—

Figure 1 is a sectional perspective view showing the bottle holder unlocked, the view being taken from the outer or hall side.

Figure 2 is a vertical section on the line 2—2 of Fig. 1.

Figure 3 is a vertical cross section on the line 3—3 of Figure 2, the slide being shown locked in full lines, and unlocked in dotted lines.

Figure 4 is an enlarged plan view of the hanger.

Figure 5 is an enlarged detail section on the line 5—5 of Figure 3.

Figure 6 is an enlarged elevation and part section of the "key".

In the drawings, in which like numerals and letters of reference indicate like parts in all the figures, 1 represents the partition wall having an outside face 2 and an inside face 3. Within this wall is located a box or cabinet comprising the bottom 4, top 5 and sides 6. The cabinet extends through the wall 1, and at each end there is provided a door frame with suitable trim 10. In these door frames are hinged at 9 the doors 8—8 respectively, there being one door at the front end of the cabinet (the outer or hall end) 55 and one door at the rear end of the cabinet (the

inner or apartment room end). Extending lengthwise of the cabinet and securely mounted to the top wall 5 thereof is a bottle hanger comprising a channeled member 11 having sides 12 with turned edges 13 to receive the mouth ring 34 of milk bottles. One or more bottles may be held, depending on the thickness of the wall 1 and the available length of the bottle hanger 11. The side walls 12 of the channeled member 11 adjacent the outer or front end thereof are slotted as at 14 to receive the pivoted cross bar 17 which serves to block the channel. The member 17 is pivoted at 18 to a lug 15 on one of the side walls 12 and at its free end it carries a lock plate 19 to which is fastened the locking tube carrying member 20, which carries the tube 20a of the locking device. The tube 20a is indented at 21 intermediate its ends to constitute spring stops for the coil springs 25 and 26 respectively.

Within the tube 20a is the latch bolt 22. The bolt 22 has a collar 22a against which the spring 25 presses to project the end of the bolt 22 into engagement with the keeper 16 that is mounted on the other side wall 12 of the channeled member 11. The tube 20a at its end is upset as at 20b and 20c, thereby constituting stops for the collar 22a and having a ring 27 that cooperates with the spring 26. The latch bolt 22 is adapted to be withdrawn to release the locking device by means of a special "key". The latter comprises a tube 28 having a head 29 through which tube and head the grapple rod 30 passes. The outer end of the grapple rod carries a spring 33 and a finger button or head 32, while the other end is split to form the spring tongs 31 which are preferably 35 of tubular form in cross section to pass over and grip the head 24 of the latch bolt 22 when the "key" is inserted into the outer end of the tube 20a.

35 is a cash and ticket box in which coins or 40 milk tickets may be placed.

In using the invention the bar 17 is locked across the channel way so as to prevent unauthorized access thereto from the outside. When the housewife desires to put empty bottles in place 45 for the milkman she may first insert the cash box 35 from the inner side of the cabinet into the channeled member and then insert the milk bottles. The inner doorway, through which the foregoing acts are accomplished, is then closed by 50 the door thereof. When the milkman comes along he inserts his "key" into the locking device after opening the outer door 8 and pulls back the latch bolt which allows the locking device to drop down to the position shown in Figure 1. 55

He may then remove the cash box 35 and the empty milk bottles. Before putting the filled bottles in place the milkman may insert the cash box into the channeled member, or the milk bottles may be put in place and the cash box inserted last, if preferred. After doing this the milkman swings the bar 17 up again and locks it by means of the locking device and the keeper 16. He then closes the outer door 8.

10 From the foregoing description, taken in connection with the accompanying drawings, it is thought that the construction, operation and advantages of my invention will be clear to those skilled in the art.

15 What I claim is:

1. In safety milk bottle containers, an inverted U-shaped channelled bottle hanger having provision in virtue of which it may be secured to an overhead support, the ends of said hanger being 20 open, a locking device adjacent one end of said

hanger, said hanger having a transverse slot in each of its side walls, said locking device comprising a hinged plate constructed to be swung into said slots across the channelway, and means to lock said plate in its position across said channelway. 5

2. In safety milk bottle containers, an inverted U-shaped channelled bottle hanger having provision in virtue of which it may be secured to an overhead support, the ends of said hanger being open, a locking device adjacent one end of said hanger, said hanger having a transverse slot in each of its side walls, said locking device comprising a hinged plate constructed to be swung into said slots across said channelway, means to lock said plate in its position across said channelway, and said last named means including a latch bolt carried by said hinged plate and a keeper carried by said channelled member. 10 15
